UNITED STATES PATENT OFFICE

139,150

DESIGN FOR A DESK WRITING UNIT OR SIMILAR ARTICLE

Edward C. Hoffmann, St. Louis, Mo.

Application March 11, 1944, Serial No. 112,863

Term of patent 14 years

(Cl. D74—1)

To all whom it may concern:

Be it known that the undersigned, Edward C. Hoffmann, a citizen of the United States, residing at St. Louis, State of Missouri, has invented a new, original, and ornamental Design for a Desk Writing Unit or Similar Article, of which the following is a specification, reference being had to the accompanying drawing, forming a part thereof, in which:

Fig. 1 is a front perspective view of a desk writing unit or similar article showing the new design; and

Fig. 2 is a rear perspective view thereof.

The essential features of my design reside in the parts shown in full lines.

I claim:

The ornamental design for a desk writing unit or similar article, substantially as shown and described.

EDWARD C. HOFFMANN.
